PREPARATION OF HEAVY METAL CYCLOPENTADIENIDES IN THE PRESENCE OF A NON-BENZENOID NITROGEN BASE

Eddie G. Lindstrom, Richmond, Calif., assignor to California Research Corporation, San Francisco, Calif., a corporation of Delaware

No Drawing. Filed Sept. 3, 1954, Ser. No. 454,233

9 Claims. (Cl. 260—439)

This invention relates to a unique and universal method of preparing metal cyclopentadienides, and is particularly applicable to the preparation of the metal biscyclopentadienyls, illustrative of which is iron biscyclopentadienyl.

The metal biscyclopentadienyls have been recently developed as a unique class of organometallic compounds. Starting with iron biscyclopentadienyl, commonly referred to as "ferrocene," this class of novel compounds has gradually been expanded through the efforts of numerous investigators to include corresponding-type compounds of titanium, chromium, manganese, cobalt, nickel, ruthenium, tin and lead. A number of methods of preparing individual members of this class of compounds has been reported, the majority of which are restrictive in their application and are peculiar to the preparation of one or more isolated members of the metal biscyclopentadienyls. In contrast to the restrictive nature of these reported methods of preparation, a unique reaction process has now been found which may be applied universally to the preparation of this class of compounds.

According to the present invention, the metal cyclopentadienides may be prepared by the liquid phase reaction of a compound containing a cyclopentadiene nucleus and possessing a reactive acidic hydrogen in the cyclopentadiene nucleus, such as cyclopentadiene, the aliphatic-substituted derivatives of cyclopentadiene or polynuclear compounds containing a reactive cyclopentadiene nucleus, with an anhydrous metal salt and, preferably, a divalent heavy metal salt when conducted in the presence of a nonbenzenoid nitrogen base having a basic dissociation constant (K_b) greater than 1×10^{-5} . The conduct of this process may be best understood by reference to its application in the preparation of the iron cyclopentadienides and particularly iron biscyclopentadienyl.

In this reaction, the iron reactant may be introduced in the form of a ferric or ferrous salt of an organic or inorganic compound containing a replaceable and acidic hydrogen, provided the reactant is introduced in a substantially anhydrous form. Examples of suitable iron compounds are the halides, sulfates, nitrates, acetates, acetylacetates, formates, propionates, etc., of which the halides, acetates and formates are preferred. Additionally, it is preferable to employ the iron salt in the ferrous form, such as ferrous chloride.

The organic reactant of the process may be cyclopentadiene or its dimer, as well as substituted cyclopentadiene or polynuclear compounds, such as indene, which contain a cyclopentadiene nucleus and an acidic and replaceable hydrogen on the cyclopentadiene nucleus. The substituted cyclopentadienes are those containing one or more aliphatic substituents attached to the cyclopentadiene nucleus and, preferably, the alkyl-substituted cyclopentadienes in which the alkyl radicals contain from 1 to 5 carbon atoms. Other substituent groups may be incorporated in the cyclopentadiene nucleus provided such substituent groups are inert to the process reactants and provide no hindrance to the formation of a cyclopentadiene anion.

Of critical importance to the conduct of the process is the presence of a nonbenzenoid nitrogen base possessing a basic dissociation constant (K_b) greater than 1×10^{-5} . Aside from the limitations on the K_b of these nitrogen

2

bases, compositionwise, they include ammonia; the primary, secondary and tertiary aliphatic amines, such as the alkyl amines and alkanol amines; and the N-heterocyclic compounds corresponding to the cycloaliphatic or saturated ring structures. These nonbenzenoid nitrogen bases, by definition, should be liquid at the temperature and pressure at which the reaction is conducted. As specific illustrations of the class of nonbenzenoid nitrogen bases falling within the scope of the foregoing definition may be mentioned the following: ammonia ($K_b 1.8 \times 10^{-5}$); secondary butylamine ($K_b 4.4 \times 10^{-4}$); diethylamine ($K_b 1.26 \times 10^{-3}$); diisobutylamine ($K_b 9.6 \times 10^{-4}$); diisobutylamine ($K_b 4.8 \times 10^{-4}$); dimethylamine ($K_b 5.2 \times 10^{-4}$); dipropylamine ($K_b 1.02 \times 10^{-3}$); ethylamine ($K_b 5.6 \times 10^{-4}$); ethylenediamine ($K_b 8.5 \times 10^{-5}$); isoamylamine ($K_b 5 \times 10^{-4}$); isobutylamine ($K_b 3.1 \times 10^{-4}$); isopropylamine ($K_b 5.3 \times 10^{-4}$); methylamine ($K_b 5 \times 10^{-4}$); methyldiethylamine ($K_b 2.7 \times 10^{-4}$); piperidine ($K_b 1.6 \times 10^{-3}$); n-propylamine ($K_b 4.7 \times 10^{-4}$); tetramethylenediamine ($K_b 5.1 \times 10^{-4}$); triethylamine ($K_b 6.4 \times 10^{-4}$); triisobutylamine ($K_b 2.6 \times 10^{-4}$); trimethylamine ($K_b 7.4 \times 10^{-5}$); trimethylenediamine ($K_b 3.5 \times 10^{-4}$); tripropylamine ($K_b 5.5 \times 10^{-4}$), etc. It has been found that, directionally, the greater the K_b of the nitrogen base, the higher the yield of desired cyclopentadienide.

In general, the temperatures of the reaction have not been found critical, although, directionally, higher yields of cyclopentadienide product have been obtained with increasing temperatures of reaction. The reaction is conducted in the liquid phase so that the reaction temperatures should be maintained substantially below the boiling point of the reactants. Pressure vessels may sometimes be employed to maintain the reaction system in a liquid state. It is preferable to operate at reasonably low temperatures to avoid excessive polymerization and corresponding loss of the cyclopentadiene reactant. In general, it is desired to conduct the reaction process at temperatures in the range of 20° to 200° C., with the preferred range of operation between 40° and 150° C.

In the operation of the process, it is desired to employ the metal reactant and the cyclopentadiene reactant in approximately stoichiometric ratio, e.g., approximately 2 mols of cyclopentadiene reactant per mol of metal reactant. The nonbenzenoid nitrogen base is preferably employed in molar excess quantities, e.g., at least 1 mol of nitrogen base per mol of cyclopentadiene reactant.

The exact mechanism of the reaction involved in the subject process has not been conclusively determined, although it appears that the nitrogen base may have a primary and secondary function as both a reaction component and a solvent. In some cases, the invention process may be advantageously carried out in the presence of a hydrocarbon solvent substantially immiscible with the nitrogen base. The function of this hydrocarbon solvent would be to remove the reaction product from the reaction zone as it is formed. A particularly desirable solvent would be the alkanes and aromatic hydrocarbons.

The resulting iron cyclopentadienides may be recovered from the reaction system by a number of conventional methods, depending upon the physical characteristics and stability of the product. The metal cyclopentadienides will range from solid to liquid and very reactive to extremely stable. The highly reactive cyclopentadienides have been found extremely susceptible to the presence of oxygen and decompose even by using stable oxygen-containing solvents. The solid products, such as the metal biscyclopentadienyls and, particularly, iron biscyclopentadienyl and the lower alkyl-substituted derivatives, may be sublimed from the reaction mixture after removal of the liquid components.

Example

1/6 mol (16 grams) of anhydrous ferrous chloride was

dispersed in 150 milliliters of piperidine ($K_b 1.6 \times 10^{-3}$). $\frac{1}{10}$ mol (20 grams) of cyclopentadiene was added and the mixture was stirred and heated at a reaction temperature of 80° to 100° C. for three hours. The reaction mixture was cooled, quenched with water, and the product was extracted in ether. The resultant ether extract was washed once with dilute hydrochloric acid and twice with water. The ether was then removed from the reaction product under vacuum in a boiling water bath. The residue consisted of crude iron biscyclopentadienyl which was obtained in a yield of 57 percent by weight.

The foregoing reaction was duplicated in further experiments at varying reaction temperatures and employing different nitrogen bases as the reaction component. Thus, iron biscyclopentadienyl was recovered in varying yields when employing diethylamine, triethylamine, n-butylamine and monoethanolamine at reaction temperatures varying between 40° to 75° C.

When employing ammonia as the nitrogen base and conducting the reaction at liquid ammonia temperatures of -33° C., no yields of iron biscyclopentadienyl were obtained. However, when conducting the reaction with ammonia under pressure in an autoclave at a reaction temperature of 80° C., the reaction was found to proceed with formation of appreciable yields of iron biscyclopentadienyl.

Additional experiments employing an aromatic amine, such as benzylamine ($K_b 2.0 \times 10^{-5}$), at temperatures of 60° to 90° C., failed to result in yields of recoverable iron biscyclopentadienyl. Also, experiments with nitrogen bases possessing a K_b less than 1×10^{-5} , as exemplified by diethanolamine ($K_b 5 \times 10^{-6}$), also failed to produce the desired product.

Obviously, many modifications and variations of the invention, as hereinbefore set forth, may be made without departing from the spirit and scope thereof, and therefore only such limitations should be imposed as are indicated in the appended claims.

I claim:

1. A process for the production of divalent heavy metal cyclopentadienides which comprises reacting in the liquid phase a cyclopentadiene compound containing a reactive acidic hydrogen in the cyclopentadiene nucleus with an anhydrous divalent heavy metal salt in the presence of a nonbenzenoid nitrogen base having a basic dissociation constant greater than 1×10^{-5} .

2. A process for the production of an iron cyclopentadienide which comprises reacting in the liquid phase a cyclopentadiene compound containing a reactive acidic hydrogen in the cyclopentadiene nucleus with an anhydrous iron salt in the presence of a nonbenzenoid nitrogen base having a basic dissociation constant greater than 1×10^{-5} .

3. A process for the production of an iron cyclopentadienide which comprises reacting in the liquid phase a cyclopentadiene compound containing a reactive acidic hydrogen in the cyclopentadiene nucleus with an anhydrous ferrous salt in the presence of a nonbenzenoid nitrogen base having a basic dissociation constant greater than 1×10^{-5} .

4. A process for the production of an iron cyclopentadienide which comprises reacting in the liquid phase an aliphatic-substituted cyclopentadiene with an anhydrous ferrous salt in the presence of a nonbenzenoid nitrogen base having a basic dissociation constant greater than 1×10^{-5} .

5. A process for the production of iron biscyclopentadienyl which comprises reacting in the liquid phase cyclopentadiene with an anhydrous ferrous salt in the presence of a nonbenzenoid nitrogen base having a basic dissociation constant greater than 1×10^{-5} .

6. A process for the production of an iron cyclopentadienide which comprises reacting in the liquid phase a cyclopentadiene compound containing a reactive acidic hydrogen in the cyclopentadiene nucleus with an anhydrous ferrous salt in the presence of piperidine.

7. A process for the production of iron biscyclopentadienyl which comprises reacting in the liquid phase cyclopentadiene with an anhydrous ferrous salt in the presence of piperidine.

8. The process for the production of the dicyclopentadienide of a divalent transition metal which comprises reacting the dihalide of said metal with cyclopentadiene in a liquid phase under anhydrous conditions and in the presence of piperidine.

9. The process for the production of the dicyclopentadienide of a divalent transition metal which comprises reacting the dihalide of said metal with cyclopentadiene in a liquid phase under anhydrous conditions and in the presence of an N-heterocyclic compound having a basic dissociation constant greater than 1×10^{-5} .
